(57) **CLAIM**

The ornamental design for a stretch leash, as shown and described.

DESCRIPTION

FIG. 1 is a front view of the stretch leash;

FIG. 2 is a bottom view of the stretch leash;

FIG. 3 is a left side view of the stretch leash;

FIG. 4 is a right side view of the stretch leash;

FIG. 5 is a back view of the stretch leash; and,

FIG. 6 is a top view of the stretch leash.

The broken lines represent stitching and form part of the claimed design.

The broken away showing in the middle portion of the stretch leash indicates that the appearance of any portion of the article between the break lines forms no part of the claimed design.
